PROCESS OF FORMING COMMERCIAL ARTICLES

John C. Bowman, Ocean Park, Calif., assignor to
 William C. Bowman, Ocean Park, Calif., and
 Ernest Roy, Los Angeles, Calif.

Application April 8, 1936, Serial No. 73,383

3 Claims. (Cl. 41—31)

This invention relates to a new and useful process and product thereof, and the principal object of my invention is, to provide a simple and relatively inexpensive process for forming commercial articles, such as tiling, tops, sides, doors, panels, borders, moldings, pedestals, and supports for use in manufacturing furniture, buildings and for ornamenting houses and the like.

With the foregoing objects in view, I form a wooden backing for each article that is faced with lacquer or self-hardening plastic or semi-plastic material that may be colored, tinted and clouded with variegated colors and which, when dried and hardened, may be polished to a finish,

resembling the smooth glaze of porcelain. A feature of the invention consists in providing the articles with ornamental designs, that appear in the polished surfaces, that are formed of metal bars, fixtures and the like that are first secured in the backings so they form cavities and channels between and around them, that are filled with lacquer or self-hardening plastic or semi-plastic material, so the top surface is level with the tops and edges of the metal parts, so the metal exposed, will be polished when the surface of the material is polished.

A feature of invention resides in the construction and ornamentation of the marginal edges which, in addition to strengthening them so they cannot be easily injured, are greatly enhanced in appearance.

Other objects, advantages and features of invention may appear in the accompanying drawing and detailed description thereof.

In the accompanying drawing which illustrates the invention, Fig. 1 is a plan view of a table constructed in accordance with my invention, a table being one of the numerous commercial things and articles that can be constructed by my process.

Fig. 2 is a side view of the table shown in Fig. 1 with one of the legs broken away.

Fig. 3 is a central cross section taken on line 3—3, Fig. 1.

Fig. 4 is a fragmentary perspective view of a table-top showing how the various parts are constructed and assembled and the edges protected by a channel iron frame.

Fig. 5 is a fragmentary sectional view, illustrating how a spined roller is utilized to perforate one side of a wooden backing.

Fig. 6 is a perspective view of a modified form of mounting the flexible strips on the backing member.

Fig. 7 is a fragmental plan view of one of the

flexible strips or bars with the end portion bent into an ornamental coil.

Fig. 8 is a side view of the flexible strip or bar and showing the prongs on its bottom edge that are driven into the perforated side of the backing.

Fig. 9 is a side view of one of the thin spacing bars or strips used in forming ornamental designs.

Fig. 10 is a cross section through one of the table legs as viewed from the line 10—10, Fig. 2.

Fig. 11 is a sectional view of a modified form of channel iron frame used for protecting the corner edges of panels, table-tops, doors and the like.

In detail, my process consists of forming backings of wood, in proper sizes and shapes for the articles that are to be produced. For illustration, if one of the articles is a table top, the backing will be rectangular in form and preferably made of three-ply veneer.

The edges of this backing 10 are enclosed by a channel-iron frame 11 that is secured in place by screws 12, and arranged so that a large portion of the frame 11 extends beyond the top surface 13 of the backing which has been perforated as designated by 14, such perforations made by a spined pressure roller 15 which, by means not shown but well understood, is actuated to force the spines 16 through the top ply of the backing 10.

The frame 11 is secured to the backing so it forms a trough like cavity that is then filled with lacquer or a self-hardening plastic or plastic material 17 that is forced so compactly in the cavity and perforations 14, that it will not crack or shrink away from the frame when dried. Also, the channel in the channel iron frame is also compactly filled with the self-hardening material, after which, the excess material is struck off to a level with the top edge of the frame and the flanges of the angle iron.

After the material has thoroughly dried, the top surface and side edges of the table top 18 are ground down until they are substantially smooth and level with the metal edges, after which the top and edges, together with the exposed metal edges of the channel irons, are highly polished.

As shown in Figs. 1, 4 and 7 to 9, thin flexible strips 19 of metal, or material such as celluloid, bakelite or pyrolin with fixtures 20, can be used to form ornamental designs in the articles; and when so used the strips are first bent, curved or coiled into proper form; and provided with saw teeth 21 on their bottom edges so they can be arranged on the perforated side of the backing 55

10 and secured thereto by driving the teeth into the back, after which the fixtures 20 are arranged in their proper places and secured by their integral nail-like extensions 22 to the backing. 5 When so arranged, they form channels between and around them within the trough formed by the edge frame.

It is obvious that the space in the channels and around the fixtures may be filled with a lacquer or self-hardening plastic or semi-plastic material which, when dry may be polished, together with the exposed edges of the bars and ends of the fixtures.

In addition to the table top 18 being formed by my process, its sides 23 and legs 24 may also be so formed. The sides 23 are enclosed by a channel iron frame 25 that has its channel filled with lacquer or a self-hardening plastic or semi-plastic material which, when dry may be polished.

20 The legs 24 may have design figures formed on their surface by securing flexible strips 19 to them and then filling the space between them with material 17 which, when in plastic or semi-plastic condition may be rounded, as shown in 25 the drawing, and polished when dry.

Instead of forming the flexible strips with prongs on their lower edges and driving said prongs into the backing member, the latter may be provided with grooves, as designated by 10a, 30 Fig. 6, and the lower portions of flexible strips 19a devoid of the prongs 21, are inserted in said grooves with the upper portions of said strips projecting a short distance above the surface of the backing.

35 It is obvious that practically all exposed parts of a piece of furniture or other structure may be formed by my improved process.

The plastic compound or material used in my improved process, is compounded so it may be colored and clouded in delicate tints and tones 40 suitable for obtaining highly artistic effects when used in furnishing bathrooms, kitchen cabinets, sinks and the like.

45 While I have shown and described one practical way of practicing my improved method, it will be understood that said method may be varied slightly in details, without departing from the spirit of my invention, the scope of which is set forth in the appended claims.

50 I claim as my invention:

1. The herein described process of forming commercial articles, consisting of first making a wooden backing and forming recesses in one face thereof, then securing a channel frame to 55 the edges of said backing so a trough is formed

on its recessed side and a channel formed around the edges of said backing, then placing self-hardening plastic material into the trough and pressing it into the recesses in the face of said backing and also filling the channel around the edges of said backing with said material, then removing the excess material so it is level with the edge of said frame and flanges of said channel, then drying the material and then polishing the exposed surfaces of said dried material together with the exposed edges of said frame. 5

2. The herein described process of forming commercial articles consisting of first making a wooden backing and forming recesses in one of its faces, then securing a channel iron frame to 15 the edges of said backing, so that a shallow trough is formed on its recessed side and so the flanges of said iron extend outwardly to form a channel around said frame, then forming a design in said trough by securing straight, curved and coiled 20 flexible strips and fixtures to said backing in a pre-arranged order to delineate the design and form spaces between and around said strips and fixtures, then impressing self-hardening plastic material into the trough to fill the spaces between 25 said strips and around said fixtures and also filling the channel in the channel frame with the plastic material, then removing the excess material to level it down to the edges of the frame and flanges of the channel iron, then drying the 30 material and then polishing the exposed surfaces thereof.

3. The herein described process of forming colored commercial articles consisting of first making a wooden backing and forming recesses in one face thereof, then securing a channel iron frame to the edges of said backing, so a shallow trough is formed on its recessed side and also so that the flanges of said iron are extended outwardly to form a channel around said frame, then 40 forming a design in said trough by securing straight, curved and coiled strips and fixtures to said backing in a pre-arranged order to delineate the design and form spaces between and around said strips and fixtures, then delivering and pressing a self-hardening plastic or semi-plastic material into the trough to fill the spaces between said strips and around said fixtures and also filling the channel in the frame with said material, then striking off the excess material to level it 45 down to the edges of the frame and flanges of the channel iron, then drying the material and then polishing the exposed surfaces thereof. 50

JOHN C. BOWMAN. 55
